BRICK HANDLING APPARATUS

John Foster Oury, Northlake, Ill.

Application September 10, 1956, Serial No. 698,762

6 Claims. (Cl. 214—653)

My invention relates to brick handling apparatus and has particular reference to a mechanism which may be used in the handling of bricks, mortar, lumber, and the like, in building construction, both for unloading from a platform truck or for the purpose of handling building material and hoisting it to a position where it can be deposited upon a scaffold where workmen, such as bricklayers, carpenters, and the like, can have the material close at hand for use in embodying it in the structure under construction.

Another object of my invention is the provision of a power operated vehicle upon which a brick handling and hoisting mechanism can be mounted and which may be used in picking up bricks which have been stacked in the form of a cube or the like, and moving such stacked up bricks from one point to another for convenience in building, storage, and the like, which can also be used for lifting such a cube of bricks and depositing it upon a scaffold adjacent the bricklayers without the necessity of carrying the bricks up ladders and the like.

Another and further object of my invention is the provision of a brick or block handling apparatus which embodies an open sided squeeze frame which can be placed in position to exert pressure upon the lowermost layer of a cube of bricks, blocks, or the like to provide a pallet which supports the bricks above the lowermost layer forming the pallet, and in which a cube of bricks can be transported from the ground, storage place, or the like, onto a scaffold where they are within easy reach and access of the workmen.

Another and further object of my invention is the provision of a brick handling apparatus which when curved over a cube of bricks or blocks automatically positions itself over a cube of bricks in such manner that the thrust of the squeeze frame is properly aligned with respect to the brick cube and that the gripping fingers engage the bottom row of bricks of the cube of bricks in a plane below the center of such row of bricks so that a secure pallet is formed to sustain the weight of the cube of bricks, without any attention, particularly upon the part of the operator.

Another and further object of my invention is the provision of a brick handling apparatus in which the squeeze frame is properly positioned over a cube of bricks regardless of the uneven condition of the ground upon which the bricks may lie or the canted position of the vehicle because of uneven ground upon which it rests so that the application of force through the squeeze frame to the cube of bricks is in the proper alignment to provide a stable cube without danger of the bricks falling, or dropping out of a cube onto workmen resulting in injury or the like to such workmen.

A further object of my invention is the provision of lifting and handling mechanisms to a well known type of vehicle for the purpose of handling bricks, blocks, mortar, and the like, on the job to eliminate the manual handling of such material which has been the practice generally followed in residences, store buildings, and the like, where such buildings are usually three stories in height but may cover a substantial area of ground.

2

These and other objects of my invention will be more fully and better understood with reference to the accompanying drawings and in which—

5 Figure 1 is a side elevational view of my improved brick handling apparatus;

Figure 2 is a front elevational view of the apparatus shown in Fig. 1;

10 Figure 3 is a top plan view of the squeeze frame and mounting connections therefor on the squeeze frame carriage;

Figure 4 is a detailed sectional view of the brick gripping mechanism;

15 Figure 5 is a vertical sectional view on lines 5—5 of Fig. 4;

Figure 6 is a detailed side view partially in elevation and partially in section of the squeeze frame and squeeze frame carriage and mounting therefor on the elevator mast taken on lines 6—6 of Fig. 7;

20 Figure 7 is a top plan view of the mechanism shown in Fig. 6;

Figure 8 is a detailed view showing a part of the squeeze frame and squeeze frame carriage on lines 8—8 of Fig. 5; and

25 Figure 9 is a view showing the hydraulic operating mechanism for the brick handling mechanism of the device.

Referring now specifically to the drawings and in which like reference characters refer to like parts throughout, a main frame 10 for the vehicle is shown

30 having forwardly extending frame portions 11, 11 to which a transverse cross frame member 12 is secured which in turn has forwardly extending side members 13 and 14 secured thereto which have axles 15 and 16 mounted therein upon which traction wheels 17 and 18 are mounted with sprocket wheels 19 and 20 being secured thereto and over which sprocket chains 21 and 22 are connected for the purpose of driving the wheels 17 and 18 as hereinafter described.

35 A caster wheel 23 is placed at the rear end of the frame 10 which is mounted in a swivel caster frame 24 secured in a bearing 25 suitably mounted to the frame 10.

An internal combustion engine 26 is mounted on the frame 10 with gear housing 27 at the forward end thereof of having trunnions 28 and 29 at each side of the housing 27 from which power shafts connected with the engine 26 extend, which power shafts are connected with the usual transmission gears in the gear housing 27, and which have sprocket wheels 30, 30 loosely mounted thereon but connected to the said power shafts by means of clutches 31, 31 each of which clutches 31, 31 may be disengaged by rods such as 32, 32 secured to operating cranks 33, to disengage the clutches 31, 31, as herein-after described.

40 Jack shafts 34 and 35 are provided which are mounted on the cross frame member 12 in bearings 36, 36 which are secured to pillow blocks 37, 37 on the cross member 12. The jack shafts 34 and 35 extend parallel with the cross frame member 12 and have sprocket wheels 38, 38 mounted on the inner ends thereof over which sprocket chains 39, 39 operate which are connected with the power shafts leading from the transmission mechanism. Each of the shafts 34 and 35 have sprocket wheels 40, 40 on the outer ends thereof which sprocket wheels 40 and 40 are connected by the sprocket chains 21 and 22 with the sprocket wheels 19 and 20 secured to the traction wheels 17 and 18 by means of which power is transmitted from the internal combustion engine 27, by means of which the vehicle supporting the balance of the operating mechanism can be transported from place to place.

which have handle portions at their rear ends and have braces 42, 42 secured to the steering bars 41, 41 and to the rear end of the frame 10, the said bars 41, 41 being spaced apart so the operator may walk between them and grasp the handle portion of each rod with each hand and steer the vehicle or control its direction by exerting a sidewise pressure upon the bars 41, 41. The rods 32, 32 lead to the clutches 31, 31 and are secured to finger levers 43 mounted upon each side of the handle portions of each of the bars 41 and provides means by which the operator may also steer the vehicle by releasing a selected clutch 31 on each end of the said power shafts, may stop the delivery of power to either one of the sprocket wheels 19 or 20 and by so doing, may turn the vehicle upon either of the wheels 17 or 18 acting as a pivot point, and about which the vehicle will then move in a horizontal plane, and the operator may also by controlling the operation of the clutches assist in steering the vehicle to any desired location which the operator may select.

A control lever 44 is provided connected by a rod 45 to standard reverse gears forming a part of the transmission mechanism, which enables the operator to operate the vehicle in either a forward or backward direction, and a throttle lever 46 is provided connected with the engine so the operator may control the speed of the engine, and the necessary power to move the vehicle depending upon the load of the vehicle and the condition of the terrain over which the vehicle moves.

A composite mast designated as a whole as 47 is mounted upon the vehicle which mast supports a squeeze frame, designated as a whole 48, as having a squeeze mechanism mounted thereon, and a squeeze frame carriage slidably mounted on the mast, for handling and transporting of brick, mortar, or the like, by the vehicle hereinabove described.

The mast 47 consists of a lower section made up of a pair of channel sections 49 and 50 each of said sections being secured to the transverse cross frame member 12 by means of brackets 51, 51 which are welded to the said member 12 and which have pivot brackets 52, 52 thereon through which pins 53, 53 extend which pins have large flat heads welded to the channel sections 49 and 50. At the upper ends of the channel sections 49 and 50 is a cross tie bar 54 which has side bars 55, 55 secured thereto also made of channel sections which are welded to the cross bar 54 and to the backs of the channel sections 49 and 50 and which hold the upper ends of the members 49 and 50 securely together in proper spaced relation with each other, with a similar cross tie bar 56 being provided intermediate of the ends of the members 49 and 50, with side bars 57, 57 being provided which are welded to the members 49 and 50 and to the cross bar 56. A pair of brackets 58 and 59 are secured to the cross bar 56 at each of its ends, and have the ends of hydraulic pistons 60 and 61 secured thereto which extend into mounted hydraulic ram cylinders 62 and 63, secured at their lower ends to brackets 64, 64 attached to the frame 10 by means of which the hydraulic cylinders 62 and 63 are anchored in position and through which the mast 46 may be tilted slightly in either a forward or rearward direction upon the pivotal mounting of the mast members 49 and 50 to the cross frame member 12 for purposes hereinafter described.

A sliding mast section consisting of a pair of U-shaped channel members 65 and 66 is provided, the channel members 65 and 66 having open sided channel faces facing each other, these members 65 and 66 having slide blocks 67, 67 welded to the back faces thereof which are fitted into the channels in the sections 49 and 50 respectively at spaced intervals, with an upper cross member 68 being provided and which is secured at each of its ends to the upper ends of the channel members 65 and 66. Slide blocks 69, 69 are welded to the edges of the flanges of the channel sections 49 and 50 at their upper

ends to act as limit stops for the upward movement of the channel sections 65 and 66 forming the upper section of the composite mast which is adapted to be raised and lowered in telescopic relation with respect to the lower mast section for the purpose of forming a support for the brick squeeze frame 48 and carriage therefor as they are raised and lowered as hereinafter described.

The squeeze frame 46 consists of a tube 70 and a second tube 71 extending parallel with the tube 70 and spaced in vertical relation with the said tube 70 and are mounted upon brackets 72 and 73 with collars 74, 74 being provided which are welded to the brackets 72 and 73 at their lower ends and surround the tube 70. The tube 71 extends through openings 75, 75 in the brackets 72 and 73, has snap rings 76 thereon adjacent the bracket 73, to prevent slippage of the tube 71 within the bracket 73, while other snap rings 77, 77 are provided which surround the larger tube 70 to prevent the slippage of the tube 70 within the bracket 73. Stub tubes 78 and 79 are mounted in the tube 70 with a plurality of spaced collars 80, 80 fixed thereon which act as bearings for the stub tubes 78 and 79 internally of the tube 70 and also hold the stub tubes 78 and 79 firmly in position with respect to the large tube 70 within which they are positioned. The tube 71 also has stub tubes 81 and 82 thereon which have spaced collars 83, 83 thereon which act as bearings for the said stub tubes 81 and 82 within the tube 71. Plates 84 and 85 are provided which are somewhat triangular in shape and are mounted on the outer ends of the stub tubes 78 and 81 and 79 and 82 respectively and have brackets 86 and 87 welded thereto, with a brick engaging finger 88 secured to the bracket 86 by means of bolts 89, 89, and a cooperating finger 90 secured to the bracket 87 in any approved means as by welding. The fingers 88 and 90 extend outward from the plates 84 and 85 and have strips of elastic material 91, 91 secured to the inner faces thereof which are brought into contact preferably with the ends of the lowermost course of brick constituting a cube and through which pressure is exerted onto the lowermost course of bricks of the cube to form the pallet which supports the upper rows of brick forming the balance of the cube. The bracket 86 has a curved slot 92 therein with a shim 93 being provided which is fitted between the outer edge of the finger 88 and the flange on the bracket 86 to provide a slight toeing in of the finger 88 so that when pressure is applied to the lowermost layers of brick, it is first applied at the tips of the fingers 88 and 90 and as pressure is continued to be applied to these fingers because of convection of the parts of the squeeze frame, equal pressure is maintained at each of the ends of the lowermost layer of bricks forming the cube so that substantially equal pressure is exerted upon this lowermost layer making sure that a firm pallet is formed of the lower layer of bricks and that individual bricks will not drop out causing damage to the equipment or injury to some workmen on the job. The elastic strips of material 91, 91 also assist in gripping the outer surfaces of brick which are usually somewhat rough and irregular and make certain that the pallet is firmly formed and that individual bricks will not drop out of the group causing damage to the machinery and to the workmen connected with its operation.

A pair of spaced brackets 94 and 95 are welded to the plate 34 and have a hydraulic ram cylinder 96 connected at one of its ends to the brackets 94 and 95 by a pin 97 and is supported by the bracket 72 intermediate its ends and has ring member 98 clamped thereover with ears 99, 99 thereon which engage with tie braces 100, 100 secured to the brackets 72 and 73 to prevent sidewise movement of the ram 96. Hydraulic hose connections 101 and 102 are provided by means to which hydraulic fluid hose 103 and 104 are connected to the ram cylinder 96 and through which the hydraulic ram is operated as hereinafter described.

A piston 105 is mounted in the hydraulic ram cylinder 96 and is connected to a tube 106 by means of a pin 107 with the tube 106 being connected to a pair of brackets 108 and 109 by means of a pin 110 so that the stub tubes 78 and 79 and 81 and 82 are moved in and out of the guide tubes 70 and 71 thereby moving the fingers 88 and 90 into and out of gripping position with the cube of bricks or blocks as the case may be.

A carriage for the squeeze frame is provided which comprises a pair of short channel sections 111 and 112 having slide blocks 113 welded to the back of the webs of the channel sections 111 and 112 and which are fitted into the channel members 65 and 66 which with the cross member 68 comprise the upper section of the mast construction with an angle 114 being welded to the edges of the members 111 and 112 and spanning the space therebetween which angle has pairs of spaced extensions 115 and 116 and 117 and 118 thereon between which the ends of the brackets 72 and 73 are positioned, each of the brackets 72 and 73 having slotted openings 119 therein through which bolts 120 pass and which afford a loose connection between the squeeze frame and the squeeze frame carriage so that when the squeeze frame carriage is dropped over a cube of bricks the carriage may cant slightly in order to properly position the squeeze frame about the cube of bricks as will be more fully described hereinafter.

A cross angle 121 is secured to the brackets 72 and 73 which has connecting angles 122, 122 at the forward face thereof to which a backboard 123 is connected at its upper edge, and which is secured near its lower edge to one of the cross braces 100 which connects the brackets 72 and 73. The backboard 123 spans the space between the fingers 88 and 90, and prevents bricks from dropping rearwardly of the squeeze frame onto some of the operating parts which bricks may come from the courses above the lowermost courses of bricks forming a pallet during the movement of the carriage or if the mast should become backward over the machine to such a degree that the bricks would have a tendency to slide off the cube. Mounted upon the backboard 123 and is secured to the backboard 123, vertical angles 124a, 124a welded to the angle 124 through which bolts 125, 125 pass through slotted openings in the angles 124a, 124a and have wing nuts 126, 126 thereon which provides for the vertical adjustment of the angle 124. The angle 124 serves as a gage when the squeeze frame is placed over a cube of bricks to properly position the fingers 88 and 90 with respect to the lowermost courses of brick so that the lower edges of the fingers 88 and 90 are substantially even with the underside of the lowermost course of brick thereby making sure that the fingers are always in proper position to grip the brick at their lowermost portions. The gage 124 can be adjusted up and down to conform to the height of a cube of bricks determined by the number of courses of brick usually four, preferably placed in edgewise relation with each other and providing for variation in height of the bricks or blocks which are being handled and which may vary slightly in width or dimension. Arms 127, 127 are provided having an angle 128 on their outer ends which angle 128 may be dropped over the forward edge of the uppermost course of bricks so its depending flange 129 prevents these bricks from becoming displaced due to vibration or a rocking movement of the mast if the vehicle passes over rough ground while the cube of bricks or blocks is being transported. Sideboards (not shown) may be provided which can be mounted on the fingers 88 and 90 to prevent loose bricks, making up the upper courses, from sliding loose if desired, although in normal operation of the device, I have not found such sideboards to be necessary.

A U-bracket 130 is mounted to the upper tie bar 68 and has an axle 131 mounted therein on which a pair of grooved pulleys 132 and 133 are mounted over which the hose 103 and 104 pass so that the ram 96 may be op-

erated when the squeeze frame is in elevated position shown in Figures 1 and 2. A sprocket wheel 134 is also mounted on the axle 131 and over which a chain 135 passes, which chain is anchored at one of its ends to the angle 114 forming a part of the squeeze frame carriage and at its opposite end is anchored to a tail bracket 136 having legs 137, 138 which are welded to the cross frame member 12.

The squeeze frame and carriage therefore is raised and lowered by a hydraulic ram comprising a tube 139 which is connected to the bracket 136 secured to the cross frame member 12, with a connecting member 142 for the tube having a pin 143 extending therethrough.

A piston 144 is mounted in the tube 139 and is connected at its upper end to a cross member 145 forming a part of the bracket 130 so that an upward thrust of the piston pushes the top section of the mast upward and as this mast section travels upward, the squeeze frame carriage and squeeze frame, is raised at the same time.

One end of the chain 135 is anchored to the frame of the vehicle while the other end is secured to the angle 114 forming a part of the squeeze frame carriage and as the top section of the mast is raised the squeeze frame and carriage are raised by the chain in a power ratio of two to one, and also at a rate of speed travel of two to one, that is the squeeze frame carriage and squeeze frame travels upward twice as fast as does the top section of the mast.

Hose pulleys 146 and 147 are mounted on brackets 148, 148 which are secured to the cross frame member 12 with the hose 103 and 104 running around the pulleys 146 and 147 respectively through which the hydraulic fluid is forced into and exhausted from the hydraulic ram 96, controlling the operation of the squeeze frame.

The hydraulic tube 139 has a connecting member at its lower end to which a hose 150 is connected through which hydraulic fluid is conveyed to and away from the tube 139 forming a part of the hydraulic ram.

For the operation of the various parts of the device hydraulically, a pump 151 is provided which is operated by a belt 152 passing over a wheel 153 mounted upon a power shaft extending outward from the engine 26. A master hydraulic valve 154 is provided having a pressure line 155 leading therefrom to the pump 151 with the lines 103 and 104 both leading to the master valve 154 which are controlled by a three way valve forming a part of the master valve, 154, by a handle 157 which controls the flow of hydraulic fluid to and exhaust from the squeeze frame ram 96 so that the operator, while moving the control handle 157, can admit fluid under pressure through the hose 103 into the squeeze ram 96 which draws the fingers 88 and 90 together to exert pressure upon the lower layer of bricks forming a cube which pressure is allowed to remain constant during the handling of the squeeze frame and cube. A pressure gage 158 is provided which registers the pressure through the pressure line 103 so that the operator is advised as to the amount of pressure being exerted upon the squeeze frame and very quickly learns to know what pressure to apply to the squeeze frame in order to provide a solid pallet for supporting the balance of the cube of bricks. The tilt rams cylinders 62 and 63 have one of their ends connected to a hose 158 which has a connecting hose line 159 leading to the master valve 154 and to a three way valve which is controlled by a handle 160 with a second hose line 161 being provided which hose line connects the opposite ends of the ram cylinders 62 and 63 together and in turn has a line 162 leading to the master control valve 154, this particular portion of the valve being a three way valve by means of which pressure can be admitted into the power ram cylinders 62 and 63 to move the mast in a backward and forward direction on its pivotal mounting, partially for balance purposes, and also to move the squeeze frame far enough over a scaffold to deposit a cube of bricks thereon after

the cube has been elevated to a sufficient height to clear the scaffolding and the vehicle moved in close enough so that when the squeeze frame is lowered, the cube of brick will rest upon the scaffolding.

An outlet pipe 164 is provided which leads from the master valve 154 to an oil reservoir 165 with a supply line 166 leading from the reservoir 165 to the pump 151. The hose 150 leads to the master valve 154 and to a two way valve controlled by a handle 163 so that pressure admitted through the valve passes to the tube 139 forming a part of the elevating ram and the upper section of the ram is moved upward carrying with it the squeeze frame to the desired height necessary to a particular operation which height I have found to be something like fourteen feet, for normal operations which permits the squeeze frame to be lifted to a height approximately twelve feet, which is adequate for the deposit of bricks, mortar, and the like, upon a scaffold ordinarily used in one and two story buildings. When the operator desires to lower the squeeze frame, he operates the two way valve through the handle 163, thereby allowing the hydraulic fluid to pass through the pipe 150 into the return pipe 164 to the reservoir 165. The weight of the squeeze frame upon the piston 144 forces the fluid from these pipes and the operator by controlling the degree of opening of the two way valve controls the rate of decent of the squeeze frame whether the squeeze frame is loaded with a cube of bricks or whether it is empty and lowered for the purpose of picking up a cube of bricks.

In the operation of the device, the operator takes his position between the projecting steering rods 41 at the rear of the machine and starts the motor 26 and through the operation of the clutch mechanism connects the transmission mechanism with the traction wheels 17 and 18 and moves the vehicle to a point where the traction wheels 17 and 18 are positioned on each side of and spaced from a pre-formed stacked cube of bricks or blocks which have previously been placed in position preferably with bricks comprising the lowermost course being in edgewise position and resting upon the ground or the floor, and the long dimension of the bricks extending transversely between the gripping fingers 88 and 90 in abutting end-to-end relation with each other. The cube of bricks may be stacked in any desired rectangular form, although I prefer that the lowermost course which ultimately becomes the pallet is placed in edgewise position in abutting end-to-end relation with each other and the additional courses above the pallet course arranged in somewhat the same manner, preferably three in number. I have found that a cube of brick which comprise about four in end-to-end relation with each other and ten in side-to-side relation making a layer comprising forty bricks and four courses in height makes a desirable sized cube, such a cube comprises one hundred sixty bricks and weighs approximately 1,000 pounds and is a desirable size to handle and can be both transported and lifted very easily and deposited upon a scaffold or any other platform as may be desired.

If the bricks are of smooth texture, particularly with respect to the bricks forming the lowermost or pallet course, strips of corrugated paper may be placed between the adjacent ends of the brick providing a cushion and a means of forming the pallet more firmly when pressure is applied thereto through the fingers 88 and 90 so that the pallet is firmly formed and the bricks are not apt to drop out of it. If the surface texture of the bricks is extremely smooth or if the surface is unusually rough, it is necessary to bring the major portion of the contacting surfaces into intimate relation with each other or to supply some medium between the surfaces of the bricks to prevent slippage so that sufficient friction is formed to hold the pallet as a unit and also to support the other layers of bricks superimposed thereon.

As the device is moved over a pallet of brick, the op-

erator, by moving the mast forward or backward, positions the gripping fingers on each side of the pre-formed cube with the backboard 123 being on a line so as to be fairly close to the side of the brick cube adjacent the machine, in which position the squeeze frame and gripping fingers are lowered over the cube until the angle 124 engages the top of the uppermost layer of bricks forming the cube adjacent the backboard 123 which gage has previously been adjusted to a proper distance to position the fingers 88 and 90 against the lower portions of the bricks forming the lower or pallet layer and in this position, the weight of the squeeze frame is supported by the angle 124 which automatically places the fingers 88 and 90 in plane parallel with the lower portions of the bricks making up the pallet course thereby accurately positioning the fingers 88 and 90 relative to the lowermost course of brick regardless of whether the cube of brick is resting upon level ground or canted slightly. The squeeze frame is loosely mounted in its carriage through bolts 120, 120 which pass through slotted openings 119 in the upper ends of the brackets 72 and 73. If the wheels of the vehicle are resting upon uneven ground or slightly canted one way or the other, the squeeze frame accurately adjusts itself to the cube of bricks. After the squeeze frame has been adjusted to the cube of bricks, the operator, through the manipulation of the valve handle 157, applies pressure through the hydraulic ram to the squeeze frame exerting pressure upon the lowermost course of brick to form a firm pallet. The operator, from experience, learns what pressure is necessary to secure this result and watches the pressure being applied through the gage 158 until adequate pressure is applied to the lowermost course of brick to form a pallet.

After the squeeze frame has been adjusted to the cube of bricks, the operator by admitting pressure to the ram tube 139 raises the upper section of the mast telescopically with respect to the lower section until the cube of bricks is free of the ground, and the vehicle can then be moved to any desired position and steered by the operator exerting pressure upon the guide handles to guide the vehicle, or through the control of the power clutches leading to the traction wheels he may guide it, to the desired point and when such point is reached, for example, adjacent the scaffold of a building, additional pressure is admitted to the lifting ram which lifts the squeeze frame including a cube of brick to a line above the scaffold upon which the workmen are employed in the laying of the brick, and the vehicle moved adjacent the scaffold until the squeeze frame and cube of brick are over the scaffold in which position the mast may be tilted forwardly if necessary to properly position the cube of brick over the scaffold in which position the squeeze frame and cube of brick are lowered until the brick rests upon the scaffold, and the operator thereupon releases the pressure of the hydraulic ram holding the brick together, the fingers freed of the cube of brick and the squeeze frame and fingers can be either lifted over the cube of brick or the entire machine can be backed away from the cube leaving it deposited upon the scaffold. As the squeeze frame is positioned around a cube of brick, the angle 128 is dropped down so that it engages the forward edge of the upper layer of bricks to prevent these bricks from slipping out of the course.

I have found that a mast construction having a lowermost section approximately eight feet in length and the uppermost section being of the same length, provides a mast of sufficient height so that a lift of fourteen feet can be obtained with the squeeze frame being lifted at least twelve feet which is sufficient height to deposit brick and the like onto the average scaffolding which is commonly used in the construction of one and two story brick buildings, stores, residences, and the like.

It will also be understood that the device may be used for lifting mortar to a position for use by workmen upon

a scaffold by the addition of a container or bucket to the squeeze frame and likewise bundles of lumber, shingles, and other building materials can also be laid across the squeeze fingers and elevated and delivered to workmen on a scaffold or at some position above the ground.

While I have described more or less precisely the details of my construction, I do not wish to be understood as limiting myself thereto, as I contemplate changes in form, the proportion of parts, and the substitution of equivalents as circumstances may suggest or render expedient without departing from the spirit or scope of my invention.

What is claimed is:

1. Brick handling and transporting apparatus comprising in combination a power driven vehicle, a vertically extending mast pivotally mounted on the said vehicle, a squeeze frame carriage movably mounted on the said mast, hydraulic means whereby the said squeeze frame carriage is raised and lowered on the said mast, a squeeze frame loosely connected to the said squeeze frame carriage, gripping fingers mounted on the squeeze frame, hydraulic means whereby the said gripping fingers are actuated to engage a cube of brick and be disengaged therefrom and a guide on the said squeeze frame adapted to engage the topmost layer of bricks forming a cube whereby the position of the squeeze frame relative to the cube of bricks is controlled and the gripping fingers are positioned in the same plane as is the lowermost course of bricks forming a cube.

2. Brick handling and transporting means comprising a power driven vehicle, a two part mast on said vehicle having a lower section pivotally mounted on the vehicle, and an upper section telescopically connected to said lower section, a hydraulic ram mounted on the vehicle at one of its ends and connected to the upper mast section at its other end whereby the said upper section may be raised and lowered, a squeeze frame carriage mounted on the said upper mast section, and a squeeze frame loosely connected with the said squeeze frame carriage and supported therefrom, brick engaging fingers on said squeeze frame, a hydraulic ram connecting the said brick engaging fingers, a pulley secured to the upper end of the upper section of the mast and a flexible bracket member secured at one of its ends to the squeeze frame carriage and anchored at its opposite end to the vehicle and extending over the said pulley whereby the squeeze frame carriage is raised and lowered with the raising and lowering of the upper mast section.

3. Brick handling and transporting means comprising a power driven vehicle, a two part mast on said vehicle having a lower section pivotally mounted on the vehicle, and an upper section telescopically connected to said lower section, a hydraulic ram mounted on the vehicle at one of its ends and connected to the upper mast section at its other end whereby the said upper section may be raised and lowered, a squeeze frame carriage mounted on the said upper mast section, and a squeeze frame loosely connected with the said squeeze frame carriage and supported therefrom, brick engaging fingers on said squeeze frame, a hydraulic ram connecting the said brick engaging fingers, a pulley secured to the upper end of the upper mast section, a chain secured at one of its ends to the said squeeze frame carriage and anchored to a fixed member of the apparatus at its other end and extending over the said pulley whereby the squeeze frame carriage and squeeze frame mounted thereon are raised and lowered with the raising and lowering of the upper section of the mast.

4. Brick handling and transporting means comprising a power driven vehicle, a two part mast on said vehicle having a lower section pivotally mounted on the vehicle, and an upper section telescopically connected to said lower section, a hydraulic ram mounted on the vehicle at one of its ends and connected to the upper mast

section at its other end whereby the said upper section may be raised and lowered, a squeeze frame carriage mounted on the said upper mast section, and a squeeze frame loosely connected with the said squeeze frame carriage and supported therefrom, brick engaging fingers on said squeeze frame, a hydraulic ram connecting the said brick engaging fingers, and a power multiplying arrangement secured to the said mast whereby the squeeze frame carriage and squeeze frame are raised and lowered with the raising and lowering of the upper section of the said mast.

5. Brick handling and transporting apparatus comprising a power driven vehicle, a mast consisting of a lower section and an upper section telescopically arranged with respect to each other, the lower section being pivotally mounted on the said vehicle, hydraulic rams fixed to the said vehicle at one of their ends and to the lower section of the said mast, a secured hydraulic ram anchored to the vehicle at one of its ends and secured to the upper section of the mast at its opposite end whereby the upper section of the said mast may be moved in relation to the lower section, a squeeze frame carriage movably mounted on the upper mast section, a squeeze frame comprising a pair of tubes in spaced parallel relation with each other, brackets connecting the said tubes with the squeeze frame carriage, sets of stub tubes mounted in the ends of the parallel extending tubes and slidably mounted therein, brackets on the outer ends of the said stub tubes, gripping fingers on the said brackets, a hydraulic ram connecting the said brackets, a backboard, a movable gauge on the said backboard whereby the position of the gripping fingers on a cube of brick is determined, a pulley on the upper end of the upper mast section and a flexible member extending over the said pulley and attached to the vehicle at one of its ends and to the squeeze frame carriage at its other end.

6. Brick handling and transporting apparatus comprising a power driven vehicle, a mast consisting of a lower section and an upper section telescopically arranged with respect to each other, the lower section being pivotally mounted on the said vehicle, hydraulic rams fixed to the said vehicle at one of their ends and to the lower section of the said mast, a secured hydraulic ram anchored to the vehicle at one of its ends and secured to the upper section of the mast at its opposite end whereby the upper section of the said mast may be moved in relation to the lower section, a squeeze frame carriage movably mounted on the upper mast section, a squeeze frame comprising a pair of tubes in spaced parallel relation with each other, brackets having slots therein connecting the said tubes, bolts extending through the said slots and the squeeze frame carriage whereby the squeeze frame is loosely connected to the squeeze frame carriage, sets of stub tubes mounted in the ends of the parallel extending tubes and slidably mounted therein, brackets on the outer ends of the said stub tubes, gripping fingers on the said brackets, a hydraulic ram connecting the said brackets, a backboard, a movable gauge on the said backboard whereby the position of the gripping fingers on a cube of brick is determined, a pulley on the upper end of the upper mast section and a flexible member extending over the said pulley and attached to the vehicle at one of its ends and to the squeeze frame carriage at its other end.
